UNITED STATES PATENT OFFICE.

FREDERICK C. BARTON, OF SCHENECTADY, NEW YORK, ASSIGNOR TO GENERAL ELECTRIC COMPANY, A CORPORATION OF NEW YORK.

CONE-TYPE LOUD-SPEAKER.

Application filed December 14, 1926. Serial No. 154,814.

My present invention relates to sound reproducing devices of the type commonly known as loud speakers and more particularly to the type of reproducing devices employing a vibrating conical diaphragm.

It is one of the objects of my invention to provide an improved flexible support for a vibrating cone diaphragm. Another object of my invention is to provide a loud speaker having a smaller vibrating diaphragm than that usually employed and which shall be efficient, rugged and capable of manufacture at moderate cost.

The novel features which I believe to be characteristic of my invention are set forth with particularity in the appended claims. My invention itself, however, will best be understood from reference to the following specification taken in connection with the accompanying drawing in which Fig. 1 represents a rear view of a cabinet with a loud speaker mounted therein which embodies the features of my invention; Fig. 2 is a detail sectional view of the drive mechanism for the vibrating diaphragm and a portion of the diaphragm; Fig. 3 is an exploded perspective view of the armature of the actuating mechanism and the connection between the armature and vibrating diaphragm; Fig. 4 is a front view partly broken away of the loud speaker unit; Fig. 5 is a plan view of the conical paper diaphragm before the ends thereof have been secured together; while Fig. 6 is a detail sectional view of the mounting for the diaphragm.

Referring to the drawing, I have indicated at 1 a cabinet having a front panel 2 provided with an opening 3 within which a diaphragm 4 may be mounted. Opening 3 may be covered by a sheet of woven or other suitable material 3'. The diaphragm 4 consists of a paper or fibrous cone about six mils in thickness and is provided with coaxial circumferential corrugations 5 spaced apart approximately $\frac{1}{4}$ inch, each corrugation having a diameter of about $\frac{1}{16}$ inch. The cone has an outwardly extending flange 6 at its base which is cut on radial lines 7 to provide a series of tabs 8 extending outwardly around the flange. The tabs 8 extend substantially across the entire width of flange 6 and are approximately $\frac{1}{4}$ inch in width and $\frac{3}{4}$ inch in length.

A relatively heavy reinforcing paper or fiber ring 9 is arranged parallel to flange 6

and secured thereto at the outer end of the tabs providing the flange with a certain degree of rigidity. A metal ring 10 of aluminum or other material is secured to the reinforced portion of the cone and flange. Ring 10 and the reinforced portion of the flange 6 are secured between the panel 2 and a metal plate 11 mounted on the inside of panel 2.

A metal plate 12 provided with an opening 13 is spaced from but secured to plate 11 and provides a mounting for the actuating mechanism for the diaphragm. The actuating mechanism or motor comprises a permanent magnet 14 provided with pole pieces 15 and 16 between which an armature 17 vibrates. The armature 17 is mounted on a spring support 18 and is reduced in cross section at one end thereof, as indicated at 19 in Fig. 3, and connected to a hollow copper drive rod 20. The end 21 of the drive rod, which is adjacent the armature, is flattened and provided with an opening 22 which fits over the reduced end of armature 17 and is soldered thereto. A brass plug 23 having an enlarged end portion 24 is sweated into the opposite end of drive rod 20.

The vibrating cone 4 is provided at its apex with an opening 25. A thin metal spider 26 having a central opening 27 is cemented to the cone and connected to the drive rod 20 by means of a small screw threaded bolt 28 which engages plug 23. The flat or enlarged portion 24 of plug 23 gives a substantial bearing for the drive rod against the diaphragm and at the same time provides means for the engagement of the screw bolt 28. The hollow copper drive rod 20 is strong yet flexible and its flattened end portion reduces the tendency of the cone 4 to vibrate laterally due to the angular motion of the armature.

The provision of circular corrugations on the cone reduces the tendency of the cone to rattle at certain frequencies. Although I have found that unusually good results may be obtained with a thin paper cone having a base seven inches in diameter and an angle at the apex of 105° , both of these dimensions may be varied slightly both above and below the figures given. In general the base of the cone will not be less than six and one half inches nor more than seven and one half inches, while the angle at the apex will usually be at least 100° and not more than 110° . The conical diaphragm may be developed

with an angle at the apex of 105° and a base having a diameter of approximately nine inches. The cone may then be cut back to provide the tabs 8, the cuts being spaced approximately $\frac{1}{4}$ inch apart providing tabs approximately $\frac{3}{4}$ inch long. The tabs, when pressed outwardly, provide a flexible supporting flange 6 and a cone having a base of approximately seven inches. The employment of a relatively small vibrating cone together with an integral flexible support therefor effects a substantial economy in the cost of manufacture, and at the same time provides a device highly efficient in operation and rugged in construction.

What I claim as new and desire to secure by Letters Patent of the United States, is—

1. In a sound reproducing device, a conical diaphragm having an integral outwardly extending flange at the base thereof, an armature, and means comprising a hollow rod con-

nected between said armature and the apex of said cone.

2. In a sound reproducing device, a conical diaphragm of fibrous material, said diaphragm having an outwardly extending flange at the base thereof, said flange comprising a series of radially extending tabs whereby the diaphragm may be flexibly supported and a reenforcing fibre ring arranged parallel to the flange and secured to the outer portion thereof. 25 30

3. A sound producing device comprising a diaphragm, a vibratory member, and a hollow rod connected to said diaphragm at one 35 of its ends and provided at the other of its ends with a flattened portion including an opening arranged to receive one end of said member.

In witness whereof, I have hereunto set my 40 hand this 13th day of December, 1926.

FREDERICK C. BARTON.
